UNITED STATES PATENT OFFICE.

WILLIAM W. McCALLIP, OF CLEVELAND, OHIO.

OVERFEED-REGULATOR FOR ROLLING-MILLS.

SPECIFICATION forming part of Letters Patent No. 331,516, dated December 1, 1885.

Application filed February 7, 1885. Serial No. 155,195. (No model.)

To all whom it may concern:

Be it known that I, WILLIAM W. McCALLIP, a citizen of the United States, residing at Cleveland, county of Cuyahoga, and State of Ohio, have invented certain new and useful 5 Improvements in Rolling-Mills; and I do hereby declare the following to be a description of the same, and of the manner of constructing and using the invention, in such full, clear, 10 concise, and exact terms as to enable any person skilled in the art to which it appertains to construct and use the same, reference being had to the accompanying drawings, forming a 15 part of the specification, the principle of the invention being herein explained, and the best mode in which I have contemplated applying that principle, so as to distinguish it from other inventions.

The object of my invention is to provide 20 certain improved means for automatically keeping from tangling the loop of working metal which forms between two stands of rolls, and is technically known as "overfeed."

In the drawings I have represented my invention by a plan in Figure 1, a vertical longitudinal section in Fig. 2, and by a vertical cross-section in Fig. 3, taken on line x x of the first figure.

The metal is herein represented as being 30 conducted from stand of rolls A to stand of rolls B by the intermediate repeater, C. Adjacent to the overfeed side of the latter is located the overfeed-regulator D, of width substantially that of the repeater. The floor a of 35 the regulator is provided with a series of transverse caps, b , arranged in consecutive order therein. This regulator-floor horizontally inclines from the repeater downward and rearwardly, while the caps are themselves horizontal. This permits the loop of working metal 40 to pass freely over the caps in movement rearward from the rolls, then to drop behind the same in successive order, and by its own gravity to be automatically prevented from again 45 getting on or over a cap that is once passed. The rear portion of each cap extends beyond its rear support, e , thereby forming a recess, d , along its back. The regulator has two side flanges, f , extending upwardly from the floor 50 thereof, and each cap is of length sufficiently less than the width of the regulator to form a

channel-guide, g , between each side thereof and the corresponding side flange of the regulator. A recess, h , is formed in each side of the cap, extending from the front of the latter 55 inwardly on an oblique line to the rear thereof, where said side recesses unite with the rear recess, d . As the overfeed passes out from the repeater, it passes laterally over the first cap, and, falling behind the same down onto 60 the floor of the regulator, it is automatically locked by the roofs of said side and rear recesses against all tendency to pass up again on the said cap. The two sides of the metal loop fit, respectively, in the two corresponding 65 channel-guides, g , and are conducted longitudinally along the same, while the curve of the loop slides along the regulator-floor in rear of the said cap. The two sides of the latter thus constitute guards to prevent the sides 70 of the loop from bending inwardly toward each other, as is their predominant tendency. The flanged sides of the regulator serve as side guards to prevent any outward bending of the loop, and thus the latter is maintained straight 75 and has movement along the length of the regulator free from tangling. At a suitable distance from the first cap, as may be determined in any given case, the loop passes over the second cap with like effect as in the first 80 instance, and so on throughout the series of caps, according to the length of the loop. The floor of the regulator is provided with a series of holes, m ; by which bolts n may adjust the caps thereon at any desired relative distance. 85 Slotted standard-sections p permit of bolts clamping them together, so as to maintain the regulator at any desired elevation and inclination.

The foregoing description has reference to 90 the form of mechanism shown in the drawings, and various modifications of the same might be suggested. I will, however, only mention that the regulator may be of any desired width greater or less than the repeater; 95 also, that the regulator may be upwardly inclined from the repeater, or horizontal, as desired. I will also add that the caps, serve as "posts," about which the loop is drawn after its rear end has passed through stand A. This 100 sliding movement of the loop along the floor, after passing around the cap, brings the metal

into line with stand B, and hence presents a straight rear end for entering said stand.

In the drawings I represent each cap as a continuous projection extending across the 5 floor of the regulator. If desired, however, it need not be thus formed, but may be broken or disconnected into two or more parts.

Other forms of embodying and using the principle of my invention may be employed in 10 substitution for the specific form herein shown. It will therefore be understood that omissions, substitutions, and changes may be made as regards the forms and parts herein set forth, provided the principles of construction embraced 15 in the following claims are retained and employed.

I therefore particularly point out and distinctly claim as my invention—

1. An overfeed-regulator provided with one 20 or more caps formed in elevation from the floor and adapted to permit the overfeed to pass over and be caught behind the same, substantially as set forth.

2. An overfeed-regulator provided with one 25 or more caps formed in elevation on its floor and adapted to permit the overfeed to pass over and be caught behind the same, said regulator having side guards forming channels between them and said caps, in which the sides 30 of the metal loop fit, substantially as set forth.

3. An overfeed-regulator having a plurality of caps respectively formed in inclined elevation to its floor, and located in consecutive order along the length of the latter, substantially as set forth.

4. In an overfeed-regulator, a cap formed in elevation on its floor and provided with a side recess which increases in depth from the front to the rear of said cap, substantially as 40 set forth.

5. An overfeed - regulator having its floor provided with one or more transverse caps

projecting in elevation therefrom, substantially as set forth.

6. An overfeed - regulator having its floor 45 provided with one or more transverse caps, the two sides of each cap constituting guards which prevent the sides of the loop of working metal from bending inwardly, substantially as set forth.

7. An overfeed - regulator having its floor provided with one or more caps formed in elevation thereon adapted to prevent the sides of the metal loop from bending inwardly, said regulator also provided with longitudinal 55 guards along the sides, extending from the floor upwardly, adapted to prevent the metal from bending outwardly, substantially as set forth.

8. An overfeed-regulator having longitudinal side guards, and provided with one or more transverse caps forming guide-channels between them and said guards, substantially as set forth.

9. The combination, with a repeater, of an overfeed-regulator having width substantially 65 same as the repeater, and provided with one or more caps located transversely on its floor, substantially as set forth.

10. An overfeed-regulator provided with a cap, and adjusting means for locating the latter 70 at different points of the length of its floor, substantially as set forth.

11. An overfeed - regulator provided with means for maintaining the loop of working metal straight, and adjusting means for locking the floor of said regulator at different elevations, substantially as set forth.

In testimony that I claim the foregoing to be my invention I have hereunto set my hand this 3d day of February, A. D. 1885.

WILLIAM W. McCALLIP.
